(57) **CLAIM**

The ornamental design for a display screen with graphical user interface for radiotherapy machine, as shown and described.

DESCRIPTION

FIG. 1 illustrates a front view of an electronic device display screen with a graphical user interface, in accordance with a first embodiment of our design.

FIG. 2 illustrates a front view of an electronic device display screen with a graphical user interface, in accordance with a second embodiment of our design.

FIG. 3 illustrates a front view of an electronic device display screen with a graphical user interface, in accordance with a third embodiment of our design; and,

FIG. 4 illustrates a front view of an electronic device display screen with a graphical user interface, in accordance with a fourth embodiment of our design.

The broken line showing portions of the electronic device illustrates unclaimed environment and forms no part of the claimed design. The broken line showing portions of the graphical user interface illustrate unclaimed portions of the graphical user interface. The outer rectangular broken line in each drawing represents a display screen of an electronic device. The claimed graphical user interfaces are not intended to be limited to the scale illustrated in the figures.
